UNITED STATES PATENT OFFICE.

GLENN E. EDMUNDS, OF COLUMBUS, OHIO, ASSIGNOR TO THE BONNEY-FLOYD COMPANY, OF COLUMBUS, OHIO, A CORPORATION OF OHIO.

MINE-CAR BUMPER.

Application filed July 23, 1927. Serial No. 208,972.

This invention relates to cars and more particularly to cars of the type used in coal mines and industrial plants.

An object of the invention is to provide an improved bumper for mine cars of this type.

After mine cars have been used for a time there is a tendency for the side walls to bulge and sag. Frequently, supporting brackets are used, but difficulty is found in obtaining a satisfactory point of attachment or base for such brackets, particularly at the ends of the car.

The present invention has as an object the provision of a bumper, preferably of integral cast construction, provided with integrally formed side wall braces and with means for mounting and supporting wall brackets of conventional type.

A further object of the invention is to provide a bumper of this character which may be readily applied to a car and which when applied will suitably brace the walls and thereby materially lengthen the useful life of the car.

In the drawings, wherein there are shown certain preferred embodiments of the invention,

Figure 1 is an end view of a car with the bumper applied.

Figure 2 is a vertical conventional view on the line 2-2 of Figure 1.

Figure 3 is a perspective of the bumper detached.

Figure 4 is a front elevational view of a bumper having a slightly modified side wall brace.

Figure 5 is an end view of a bumper having another form of brace.

Figure 6 is an end view of a car provided with another form of bumper, the parts broken away to show part of the bumper in cross section.

Figure 7 is a horizontal sectional view with a portion of the bumper top wall broken away.

Figure 8 is a fragmentary side elevational view of the car provided with the same form of bumper shown in Figures 6 and 7, and

Figure 9 is a fragmentary elevational view showing the bumper of Figures 6, 7 and 8 having associated therewith a separate wall supporting bracket.

Referring to the drawings for a more detailed description, 10 indicates a conventional

form of mine car provided with a floor 11 (Fig. 2) having resting thereon and extending longitudinally of the car a metallic draw strap or bar 12. The end of the flooring is protected by a bumper 13 having a top portion or web 14 and a depending front or apron 15. The under surface of the web 14 is transversely channeled by providing the slightly raised boss 16 for the purpose of receiving the end of the draw bar 12 and the raised section is formed with a plurality of openings 18, 19 and 20 through which may be passed suitable means serving as part of a coupler.

In Figure 2 there is shown an anchoring tongue 21 fastened in position by means of a bolt 22, the tongue having a squared pin 23 extending into the opening 20 whereby it is held against rotative movement therein. Ribs 24 projecting upwardly from the extension 16' of the bumper section 16 assist in preventing lateral movement of the tongue 21 which may serve as anchoring means for a portion of a coupler.

Adjacent the ends of the bumper the same is provided with side wall braces 25 which extend upwardly above the plane of the top web 14 and are adapted to resist any tendency of the side walls to sag or spread apart during use of the car. In the form of the invention illustrated in Figures 2 and 3 these braces or brace portions are substantially vertical and are thus adapted for use with a car having the side wall formation shown in Figure 1.

The braces may be provided with suitable openings 26 to serve as means to secure portions of the side walls as by receiving rivets 27. These same rivets may also serve to attach wall brackets 28, the lower ends of which rest upon outwardly projecting shoulders 29 extending beyond the braces in the ends of the bumper.

It will be noted that the entire bumper is an integral casting and that its simple construction enables it to readily be applied either during manufacture of the car or when repairing a car after use.

Referring to Figure 4, the bumper shown is provided with braces having substantially vertical sections 31 and sections 32 inclined outwardly with respect thereto. A reinforcing web 33 is formed beneath these sections. This type of brace is adapted for use with a car similar to that shown in Figure 1 and its

use makes it unnecessary to employ the separate supporting brackets 28.

The form of bumper shown in Figure 6 is similar to that of the figures previously described except that the braces 34 have supporting portions arranged in a single plane as distinguished from the form of Figure 4 in which different sections of the braces are arranged in distinct planes. It will be understood that this type of brace is intended for use with a car the side walls of which incline upwardly from the floor at a different angle than in the form of car illustrated in Figure 1.

In Figures 6, 7 and 8 there is shown a bumper similar to that of the views previously described except that the substantially vertical brace portions 35 are formed with offset or channel portions 36 for the purpose of providing clearance for side wall bands or straps 37 such as are commonly used in certain types of mine cars.

Moreover, as will be observed, this bumper is provided with the shoulders 38 extending outwardly at the ends of the bumper beyond the braces so that an additional supporting bracket may be readily attached to the bumper and supported by these shoulders if desired.

Referring to Figure 9, the bumper shown is identical with that illustrated in Figures 6, 7 and 8, but the same has associated therewith instead of the side reinforcing band or strap 37 a bracket 40 having lug portion 41 extending downwardly into the channel formed between the brace and the car side wall, the bracket being attached to the wall and brace as by the bolts 42.

Obviously, in the type of bumper as illustrated in Figures 6 and 9, as well as in the form illustrated in Figure 4, the formation of the integral braces may be varied to render unnecessary the use of a separate supporting bracket in which event the integral upwardly extending wall brace would be provided as illustrated in Figure 4 with an upper inclined section corresponding to the supporting surface 40 of the bracket shown in Figure 9.

It will be understood that the invention is not limited to the details of the construction described and that it comprehends such modifications as come within the scope of the following claims.

I claim:

1. An integral bumper casting for a car of the class described comprising a top portion and integrally formed side wall brace portions extending upwardly and outwardly above the plane of said top portion adjacent the ends of the bumper.

2. An integral bumper casting for a car of the class described comprising a top web por-

tion and integrally formed side wall brace portions extending upwardly above the plane 65 of said top web portion adjacent the ends of the bumper, and substantially horizontal shoulders extending outwardly at the ends of the bumper beyond said brace portions.

3. An integral bumper casting for a car of 70 the class described comprising a top web portion and integrally formed side wall brace portions extending upwardly above the plane 75 of said top web portion adjacent the ends of the bumper, said brace portions being provided with means for attaching wall brackets.

4. An integral bumper casting for a car of the class described comprising a top web portion and integrally formed side wall brace portions extending upwardly above the plane 80 of said top web portion adjacent the ends of the bumper, said brace portions being provided with means for attaching wall brackets, and bracket supporting shoulders extending outwardly at the ends of the bumper 85 from said brace portions.

5. An integral bumper casting for a car of the class described comprising a top portion and integrally formed side wall braces extending 90 upwardly above the plane of said top portion adjacent the ends of the bumper, said brace portions being vertically channeled to receive side wall bands or the like.

6. An integral bumper casting for a car of the class described comprising a top web and 95 integrally formed side wall braces extending upwardly above the plane of said top web adjacent the ends of the bumper, said brace portions being vertically channeled to receive side wall bands or the like, and substantially horizontal shoulders extending outwardly from 100 the braces at the ends of the bumper and at the base of each brace.

7. An integral bumper casting for a car of the class described comprising a top portion 105 and integrally formed side wall brace portions extending upwardly above the plane of said top adjacent the ends of the bumper, said brace portions being vertically channeled to receive side wall bands or the like and being 110 provided with means for attaching wall supporting brackets.

8. An integral bumper casting for a car of the class described comprising a top web and integrally formed side wall braces extending 115 upwardly above the plane of said top web adjacent the ends of the bumper, said brace portions being vertically channeled to receive side wall bands or the like and being provided with means for attaching wall supporting 120 brackets, and shoulders extending outwardly at the ends of the bumper beyond said braces.

In testimony whereof I have hereunto set my hand.

GLENN E. EDMUND.
